TABULATING MACHINE

Harold Hall Keen, Letchworth, England, assignor, by mesne assignments, to International Business Machines Corporation, New York, N. Y., a corporation of New York

Application June 27, 1931, Serial No. 547,199
In Great Britain July 17, 1930

10 Claims. (Cl. 235—92)

This invention relates to record controlled accounting and statistical machines of the type which may be controlled by means of grouped cards and arranged to print a group of items 5 read from the cards and the totals of the items in each group on a series of sheets which may comprise successive portions of a continuous strip.

In such machines the various items read from the cards are printed and entered in accumulating mechanism or totalizers. When the last card 10 of a group is read, automatic group control mechanism is called into action and thereafter causes the machine to go through one or more total and reset cycles during which the totals 15 on some or all the accumulators are printed and those accumulators are reset. In order that each group of items shall be printed on a separate sheet, sheet feeding means is provided which is brought into operation by the group control 20 mechanism to feed the sheet out of printing position after the totals have been printed and to feed the next sheet into printing position. On the completion of this last operation an automatic re-start mechanism comes into action to 25 cause the machine to resume operations on the next group of cards. Thus, each group of items is printed in a separate record sheet or separate portions (hereinafter referred to as a "sheet") of a continuous strip or web of record material. 30 It frequently happens that a group of items is too numerous to be accommodated on a single sheet and an "entry control" device is therefore provided which device is arranged to count the number of lines of items printed on each sheet and 35 to stop the machine as soon as the maximum number of lines that can be accommodated has been printed. A machine of this kind is described in U. S. application Serial No. 287,549, filed June 22, 1928, by F. M. Carroll now Patent 40 No. 1,909,571.

The operation of a machine of this type now known in the art is automatic only so long as each group of items can be printed on a separate sheet and the machine stops when a group can- 45 not be printed on a single sheet. Under the latter conditions, the operator has hitherto had to manually initiate the following operations:—render the automatic re-start mechanism inoperative; initiate a progressive total printing cycle in which 50 totals are printed but the accumulators are not reset; a sheet feeding operation of the sheet feeding mechanism; a second progressive total printing cycle so that successive identical totals are printed at the foot of the old sheet and head of 55 the new sheet; render the automatic re-start

mechanism operative; and, finally, reset the entry control device which last operation restarts the machine. It is apparent that numerous manual operations are required so that time is wasted and the possibility of error is large.

It will be understood that the term "progressive total" as used above and hereinafter means a total which is printed and retained in the accumulator without a subsequent clearing operation to reset the accumulator to zero. The term 60 "progressive total printing cycle" will refer to a total printing cycle in which the accumulators are not cleared while the expression "total printing and resetting cycle" will be used to refer to a total printing operation which includes clearing 65 of the accumulators after the total has been printed. In some instances it may be found desirable, in preparing a statement from one or more related groups of records, to reset one or more accumulators after printing the totals there- 70 in without resetting other accumulators.

It is desired therefore, that the term "progressive total" be construed broadly as including a total printed during a mixed cycle of operations in which only certain accumulators may be reset 80 and the total on said accumulators printed without resetting the other accumulators and that the term "progressive total printing cycle" previously defined be considered as applicable to such a cycle in which only certain of the accumulators may be 85 reset while others are not reset.

The foregoing paragraph will be more clearly understood if it is noted at this point that, in the embodiment of the invention to be explained hereinafter, it may sometimes happen that it is 90 desired to print a total from a balance counter without clearing the latter and at the same time print the total from and clear a counter devoted to accumulating entries from a complete group of records. This situation may occur when it is 95 desired to print the debit and credit items of a single group on separate forms with the balance of account both at the bottom of the first form printed and at the top of the succeeding form. Example IV, described hereinafter, is an illustration 100 of the foregoing situation. Other mixed cycles may sometimes be desired, as for instance, the one occurring after the change in major group number in Example V hereinafter described.

According to the present invention there is provided a record-card-controlled accounting and statistical machine of the above type in which the entry control device is arranged to come into action after a predetermined number of lines 110

have been printed on a sheet to initiate automatically (1) a progressive total printing cycle (2) an operation of the sheet feeding means (3) resetting of the entry control device, (4) a second progressive total printing cycle, and (5) restart line printing operations. Thus, when the maximum number of entries have been made on a sheet, the machine will proceed automatically to print a carry forward total at the foot of the sheet, feed a new sheet to the printing line, print the carry forward total at the head of this new sheet, and resume the printing operations with the remaining cards of the same group or a related group.

15 If the last entry of the maximum number of entries is also the last entry from a group of cards, both the entry control device and the automatic control mechanism will tend to come into action simultaneously or, further, the line spacing operation or operations (usually two) occurring during a total printing and resetting cycle initiated on a change of group may bring the entry control device into action to again initiate a progressive total printing cycle. In the first case, a total printing and resetting cycle would occur simultaneously with a progressive total printing cycle while in the second case they would occur in succession.

It is desirable that one of these two ways should be followed irrespective of whether the change of group occurs at the last entry or at an earlier entry. Therefore, another feature of this invention is the provision, in a record-controlled machine, of mechanism for initiating a progressive total printing cycle and an operation of the sheet feeding means, means for bringing the initiating mechanism into action and arranged to be operated by the entry control device after the said predetermined number of lines have been printed, and means for placing the initiating mechanism under the control of the automatic group control mechanism and arranged to be operated by the entry control device after a lesser number of lines have been printed, the automatic group control mechanism being arranged to bring the initiating mechanism into action, when so placed under its control, at a time determined by the automatic group control mechanism.

In many cases there will be no progressive totals to print and, in order to save time in the operation of the machine, the automatic group control mechanism is preferably arranged, on coming into action, to initiate a total printing and resetting cycle, to bring the initiating means into action so that a progressive total printing cycle is initiated and occurs simultaneously with the said total printing and resetting cycle.

The lesser number referred to above is less than the predetermined number of entries by the number of line spacing operations occurring during a total printing cycle. Thus, if two line spacing operations occur during a total printing cycle, any change of group occurring when the antepenultimate, penultimate or ultimate entry in a sheet is made will result in a total printing and resetting cycle which is also, potentially at least, a progressive total printing cycle.

Conveniently, the sheet feeding mechanism is arranged to reset the entry control device on the conclusion of a sheet feeding operation, and said device is arranged to initiate a progressive total printing cycle as soon as it has been reset to its starting position.

A preferred embodiment of the invention will now be described, by way of example only, with

reference to the accompanying drawings, in which:

Figures 1 and 2 taken together form a circuit diagram for a record-card-controlled statistical machine;

Figure 3 is a front elevation of the machine;

Figure 4 is an enlarged plan view of the means for controlling sheet feeding operations;

Figure 5 is a vertical section on the line 5—5 of Figure 4, the section having been rotated 90° in a counterclockwise direction so as to show the parts in their normal erect relation in the machine.

Figure 6 is a vertical section on the lines 6—6 of Figures 3 and 7;

Figure 7 is a front elevation of the parts shown in Figure 6;

Figure 8 is a front elevation of an entry control device with its cover and dial plate removed;

Figure 9 shows the means employed for resetting the entry control device;

Figure 10 is a detail view of certain parts shown in Figure 9, and

Figure 11 illustrates the printing mechanism employed.

General arrangement

The general construction of the statistical and accounting machine will be described first only so far as is necessary for an understanding of the invention. As shown in Figure 3, the record cards are placed in a supply hopper 203 from which they are fed, one at a time, past upper and lower brushes UB and LB (Fig. 1), respectively, by card feeding mechanism of well-known construction which delivers the cards to a discharge hopper 204.

The upper brushes UB are arranged to read the group numbers of one card while the lower brushes LB are reading the group numbers of the preceding card and controlling the printing and entry of amounts. The machine is provided with accumulating mechanism which may include five counters or accumulators 200 of the usual construction in which the items read from the cards can be accumulated, and with printing mechanism 201 by which the items read can be printed on a continuous record strip or web. The accumulators 200 may be of the type described in Patents Nos. 1,307,740 and 1,534,531 while the printing mechanism is substantially similar to the one described in Patent No. 1,762,145. The strip is divided by pre-printed headings into equal sections or lengths (which are hereinafter referred to as "sheets") so that the strip can be subsequently cut or severed into separate sheets each having a pre-printed heading. The printing mechanism can also be operated under the control of the counters to print the totals standing on the counters. During listing operations the printing mechanism is driven by a listing shaft (not shown) which is driven by a card feed motor FM (Figures 1 and 3). Certain cams, driven by the listing shaft operate contacts designated by the letter "L". During total printing operations the printing mechanism is driven by a total shaft (not shown) which is itself driven by a reset motor RM (Figures 1 and 3) through a one-revolution clutch (not shown) which will be referred to as the reset clutch. The total shaft also operates a number of cam contacts herein-after designated by reference numerals having prefixes "P" and "LP".

The reset motor also drives a reset shaft 202 (Figures 3 and 4) through the reset clutch, and

suitable gearing so arranged that the reset shaft is idle during the first half of a total printing cycle, but turns through one revolution during the second half of such a cycle. Each counter 5 can be reset by a gear wheel 205, individual to that counter these wheels being loosely mounted on the reset shaft. One part 206 of a counter resetting clutch 206-207 is secured to each gear wheel and the other part 207 is splined on the 10 reset shaft and is spring-pressed away from the part 206.

Each counter resetting clutch is controlled by a separate clutch magnet 14 (Figures 1 and 3) which may be energized to effect engagement of the associated clutch so that the corresponding counter or accumulator 200 will be reset to zero when the reset shaft rotates. As this mechanism is now well known it will not be described in greater detail. A substantially similar construction is described in Patent No. 1,933,308 granted 20 to James W. Bryce.

The record strip passes round a platen 208 (Figures 3 and 11) which is turned one step after each printing operation by a pawl and ratchet device (not shown) in order to line space the strip. The arrangement is such that, when the printing mechanism is driven by the listing shaft, a single line spacing movement occurs, while, when the total shaft is in operation, two line spacing movements occur. This is done in order to provide a blank space after each total so as to separate that total from the first entry of the next group of cards. The mechanism for feeding the paper strip to accomplish the foregoing result is fully 35 explained in application Serial No. 639,153 filed May 15, 1923, by Clair D. Lake, now Patent No. 1,822,594.

Sheet feeding mechanism

40 The platen is secured to a platen shaft 209 (Figures 3, 6 and 7) which slides in a sleeve 210 secured to the frame of the machine. A single toothed disc 211 is loosely mounted on the sleeve and carries two driving dogs 213 secured to the 45 ends of a member 214 which is splined on the shaft 209 so that the disc and shaft rotate as one. A second disc 215 is mounted on the sleeve 210 and carries a driving pawl 216 which co-operates with the tooth 212 on the disc 211. This disc 215 is 50 coupled by means of a train of gearing 217 to a gear wheel 218 (Figures 3 and 4) secured to a driven clutch member 219 which is loosely mounted on the resetting shaft 202 and is confined axially by a frame member 220 supporting the shaft 55 202 and a collar 221 pinned to the resetting shaft.

A driving clutch member 222 is mounted on the shaft and has dogs 223 which extend through slots 224 in the collar 221 so that the member 222 rotates with the shaft 202. The driven clutch member 219 is provided with slots 225 to receive the dogs 223 on the driving member 222 and a spring 226 located between the collar 221 and the driving member 222 serves to move the latter away from the driven member so that normally the dogs 223 60 do not project into the slots 225 in the driven member. The clutch just described can be engaged by energizing a sheet feeding magnet 20 when then attracts its armature 227, pivoted at 228 and engaging at its free end the right end of 65 a slide 229, the left end 230 of which engages the clutch member 222. When the armature is attracted it moves the slide 229 and the clutch member 222 to the left (Figure 4) thereby effecting engagement of the dogs 223 with the slots 225.

70 A cam 231 (Figure 5) secured to the wheel 218

has a recess 233 in which rests a tooth on the end of a pivoted lever 234. This lever in turn engages a rod 235 mounted to slide in a bracket 236 and arranged to co-operate with the middle blade of contacts 64 and 66 (Figure 4). The parts are normally in the position shown in Figure 5. After the magnet 20 has been energized and the cam 231 has started to rotate with the resetting shaft, the cam 231 cams the lever 234 and rod 235 to the right (Figure 5), opening the contacts 66 without closing the contacts 64. Towards the end of a revolution of the cam, a cam rise 232 rocks the lever further to the right to close the contacts 64. When the resetting shaft reaches its normal position the tooth in the end of the lever 234 drops 80 into the recess 233 in the cam 231 so that the contacts 66 close and the contacts 64 open.

This mechanism constitutes the sheet feeding mechanism hereinbefore referred to and its operation is as follows: As items are listed the platen 208 is fed round step by step and the shaft 209 turns correspondingly and consequently the tooth 212 on the ratchet disc 211 is moved step by step away from the driving pawl 216. When the sheet feeding magnet 20 is energized, the gear wheel 100 218 is clutched to the resetting shaft 202 so that the pawl disc 215 is coupled to shaft 202 which then rotates and drives the pawl disc. During the first part of the movement of the pawl disc, the ratchet disc 211 and the platen are stationary but, 105 after a movement depending upon the number of entries that have been made, the pawl 216 engages the tooth 212 and the ratchet disc 211 together with the platen 208 are rotated with the pawl disc through the remainder of the latter's 110 movement. Assuming that the total movement of the pawl disc is equal to twenty line spacing movements of the platen and that ten entries have been made, then the pawl disc will commence to drive the platen when it has completed half its 115 movement (equivalent to ten line spacings) and will move the platen through an amount equivalent to ten line spacings. The ratio of the gearing through which the pawl disc 215 is driven can be varied by removing the gear wheels 217 and 120 substituting wheels of different diameter, therefore the movement of the pawl disc can be made equivalent to the number of line spacings necessary to feed the record strip the length of one sheet. 125

Entry control device

The machine is provided with an entry control device 240 (Figures, 3, 8, 9 and 10). This device comprises a pair of ratchet wheels 241 and a circular dial plate 242 having a circular series of holes 243, both of the wheels 241 and the plate 242 being secured to a spindle 246, which is mounted in a back plate 240a of the device. Concentric with the dial plate is a pointer 244, carrying at one end a spring pressed pin 245 which is adapted to pass through the holes 243 in the dial plate 242, and extend to the other side thereof. The holes in the dial plate are suitably numbered to indicate the number of lines which are to be printed and the pointer is adjusted to the number of lines required and locked by pushing the pin 245 into one of the holes 243. An operating-pawl 250 co-operates with the ratchet and is pivoted at 251 on the armature 252 of an 140 electro-magnet 11 so that, whenever the electro-magnet is energized, the pawl 250 is operated to feed the ratchet 241 through one tooth space. A non-return detent 253 serves to hold the ratchet 145 in its advanced position. The magnet 11, which 150

will be referred to as the entry counting magnet, is energized, as will be apparent hereinafter, whenever the platen is advanced one line space so that the ratchet wheel 241 together with the screw threaded shaft 246, the dial plate 242, and the pointer 244 are moved through one tooth space in a clockwise direction (Figure 8) for each line spacing movement.

After a certain movement, determined by the position of the pointer 244 on the dial plate, the pin 245 on the pointer will engage one end of a bell crank 254, the upper portion of which extends just far enough into the path of the pin 245 to be cammed downwardly (Fig. 8) whenever said pin strikes the end of the bell crank, thereby rocking the bell crank 254 an extent sufficient to close a pair of normally open contacts 60. The bell crank 254 is so positioned with respect to the other parts of the mechanism

15 that the contacts 60 close when the entry before the next-to-the-last entry is made on the record sheet and will be termed the "anticipatory contacts" hereinafter since they anticipate the end of the record sheet. In the following descrip-

20 25 tion the terms "ultimate entry", "penultimate entry", and "ante-penultimate entry" will be used in referring to the last entry, the next-to-the-last entry, and the entry prior to the next-to-the-last entry, respectively. Thus, the contacts 60 close on the ante-penultimate entry.

30 The pin 245 may move two additional steps further to engage the upper end of a bell crank 255 when the last or ultimate entry is made. The upper end of the bell crank 255 extends upwardly

35 40 an amount sufficient to cause said bell crank to rock in a counterclockwise direction when the pin 245 strikes the bell crank thereby closing a pair of contacts 45 to initiate a sheet feeding operation by energizing magnet 20 in a manner to be described in detail later herein. If the ante-

penultimate entry is made from the last card of a group, a total printing and resetting cycle will occur and will be accompanied by two line-spacing operations and the pin 245 will be moved

45 50 two steps and will close the contacts 45. Thus, if a total is printed after the antepenultimate entry, it will be followed by a progressive total printing cycle. This latter cycle will not, in most cases, result in any totals being printed but

55 60 it may in some cases result in totals being printed. The function of the anticipatory contacts 60 is to combine these two successive cycles, initiating prematurely the same series of operations as the contacts 45 do whenever a total printing

55 60 65 and resetting operation follows the antepenultimate entry or the penultimate entry into a sheet. Thus, when the anticipatory contacts 60 have been closed and a change in group occurs, a total printing cycle occurs in which those

60 65 70 counters affected by the change in group are reset and the rest (if any) are not. Thus, as regards the latter counters, the cycle is a progressive total printing cycle.

75 The feed pawl 250 is provided with an extension 256 which overlies the non-return detent 253 and the latter is provided with a pin 257 to the left (Fig. 8) of an offset lug 258 of a pivoted lever 259 connected at 260 to a second lever 261, both levers being pivoted at 262. The second lever 261 is connected to the armature 263 of a reset magnet 16 and when this magnet is energized, it attracts its armature and rocks both the levers 261 and 259 clockwise.

75 When the lever 259 is rocked, it withdraws the

non-return detent 253 and the feed pawl 250 from engagement with the ratchet wheel 241.

The entry control device is reset by the energization of a solenoid 100 which is mounted upon rods 249, extending behind the back plate 240a of the device. The spindle 246 extends through the back plate 240a and has a sleeve 246a pinned to its rear end, a thrust bearing 248 being interposed between the sleeve and the back plate. A sliding armature 247 is mounted in the solenoid and is provided with two key ways 247a engaging two keys 100b on a plate 100a which is adjustably secured to the end of the solenoid 100 (see Figure 10). The armature 247 can thus move axially but is prevented from rotating. The front end 247b of the armature is formed with a quick pitch thread which is engaged by the ends of three equally spaced screws 246b on the sleeve 246a.

As the ratchet wheel 241 and spindle 246 are stepped round in the direction of the arrows (Figures 8 and 9) the sleeve 246a rotates and moves the armature 247 to the right (Figure 9) out of the solenoid 100. When the solenoid is energized it moves its armature to the left (Figure 9) and the latter rotates the sleeve 246a and spindle 246 counterclockwise (Figure 8) until a stop 264 on the ratchet wheel engages a fixed stop 264a.

Referring to the lower left-hand portion of Figure 1, the reset magnet 16 and solenoid 100 are connected to the fixed contact 66 of the contacts 64, 66, which it will be recalled are controlled by the cam 231. Towards the end of a reset cycle cam 231 closes the contacts 64 and a 100 circuit is then established from the left side 13 of the current supply line through a relay magnet 65, the contacts 64, a line 62, and cam contacts L P 10 (now closed) to the right side 12 of the current supply line.

105 The magnet 65 also closes its contacts 63 to hold this circuit. When the reset shaft 202 and cam 231 come to rest at the end of a total printing operation and after the old sheet has been fed out and a new sheet fed in, the contacts 66 close and establish a circuit extending through the magnet 16 and solenoid 100 in parallel and through the contacts 66, the contacts 63, the line 62, and the cam contacts L P 10. The entry control device is thus reset and, on the dial plate 242 reaching its normal position, a projection 266 on the plate rocks a bell-crank lever 267 to close a pair of contacts 17. The closure of these contacts initiates a progressive total printing cycle during which "brought-forward" totals (if any) are printed at the head of the new sheet. During the first half of this last cycle the cam contacts L P 10 open to de-energize the magnets 65 and 16 and the solenoid 100.

110 115 120 125 130 135 140 145 150 The entry control device may also be reset and the machine started by pushing a rod 268 to the left (Figure 8) in its bearings 269. The rod carries a collar 269a which, when the rod is moved to the left, closes a pair of contacts 113. These contacts are in parallel (Figure 1) with the contacts 63 and, when closed, complete the circuit for the magnet 65. Since the contacts 66 are closed because the reset shaft is in its home position, the magnet 16 and solenoid 100 will also be energized to reset the entry control device and effect closure of contacts 17. The machine will then go through a progressive total printing cycle at the conclusion of which the motor FM will be automatically restarted. The automatic restarting of the feed motor FM is effected by closure 150

of cam contacts P4 near the end of a total printing cycle. The operation of the automatic restarting circuit is more fully described in Patent No. 1,762,145.

5 It will be seen that in this device the ratchet and dial plate have a fixed initial position but that the operative position of the device by which it becomes effective to control the machine is determined by the adjustment of the pointer on 10 the dial plate. The functions of various contacts controlled by the entry control device will be described in detail with reference to the circuit diagram hereinafter.

Circuit diagram

15 Referring to the circuit diagram the feed motor FM and reset motor RM are controlled in the usual way by a group of circuits and contacts shown in the upper part of Figure 1. As these 20 circuits are well known they will not be described, but a detailed description of the starting circuits may be had by reference to Letters Patent No. 1,762,145 granted June 10, 1930. The feed motor FM continues to operate so long as the cards are 25 fed past the brushes and a pair of normally closed motor control contacts MCC remain closed. These contacts are controlled by a motor control relay magnet MC which may be energized to open the contacts MCC and interrupt the circuit 30 of the feed motor.

Counters and printing mechanism

35 The accumulators and printing mechanism are similar to those described in Patent No. 1,822,594 already mentioned to which reference may be had for a more detailed description of their arrangement. As usual, a printing bank is associated with each accumulator or counter.

40 In order to simplify the drawings, only the circuits for the first or lowest denominational orders of the counters and the circuits for printing the asterisk adjacent totals have been shown in Figure 2, these circuits being designated by the numeral "1" and the symbol "*", respectively, in 45 each counter.

The circuits for only the second, third and fourth counters (counting from the left, Fig. 3) and associated printing banks are illustrated diagrammatically in Figure 2 and normally receive 50 their current from the supply lines 12 and 13 but are supplied from a line 73 through switches 81 during the printing of the progressive totals. Each counter is provided with a bus bar 69 which can be connected to the line 13 through a pair of contacts 71 or to the line 73 through a pair of contacts 72 and a switch 81, there being separate contacts 71, 72, associated with each counter. When the counter resetting clutches 206-207 are 55 disengaged, the contacts 72 are closed so as to connect the bus bar 69 to the line 73 but the operation of the corresponding counter resetting clutch, as a result of its magnet 14 being energized, opens the contacts 72 and closes the contacts 71, connecting the bus bar 69 to the line 13. The line 73 is connected to the line 13 through 60 normally open contacts 74 (Figure 1) controlled by a relay magnet 67-68 having a double winding.

65 Each printing bank has an asterisk type bar 280 (Figure 11). This type bar is provided with an asterisk type 281 in the position corresponding to the digit "9" on amount printing type bars and is arrested with the asterisk type in the printing position when a total is being printed so that 70 the total may be identified by an asterisk. The

printing mechanism is arranged to print the symbol "F" against all progressive totals to signify that they are "carry forward" or "brought forward" totals and not the final totals which are indicated by the asterisk. The asterisk type bar is therefore provided with an "F" type 282 in the position corresponding to the digit "1".

75 Each asterisk type bar is provided with a controlling magnet 86 which, when energized, releases a detent 283 to engage a rack 284 and arrest the type bar in a position determined by the time in the cycle at which the magnet is energized.

The circuit for the asterisk magnet 86 extends from the supply line 12 through the lower cam contacts P2, which close as soon as the total shaft begins to move, to the asterisk line 85 thence in parallel through the asterisk magnets 86, contacts 88, the bus bar 69, and the contacts 71 to the supply line 13. This circuit is completed prior to the "9" time in the cycle where any magnet 14 is energized to close contacts 71 and results in the corresponding type bar 280 being arrested with the asterisk type in the printing position. If, however, a progressive total printing cycle is initiated, the counter resetting clutches 206-207 will not be engaged consequently the contacts 72 will be closed and the contacts 71 opened. The contacts 88 of each counter are also controlled by the corresponding counter resetting clutch magnet 14 which closes said contacts when the clutch is engaged and opens them when the clutch is disengaged. It will be clear that during a progressive total printing cycle none of the counter resetting clutches will be engaged and all 110 the contacts 88 will be open. The asterisk magnet circuit will thus not be completed until a pair of contacts 89 close. These contacts 89 are closed mechanically just prior to the "1" time in the cycle by any suitable means, such as the means disclosed in Patent No. 1,379,268 for operating contacts 146 in said patent, so that the asterisk magnet is energized at this time to arrest its type bar with the "F" type in the printing position. 120

Automatic control

The machine is provided with automatic group control mechanism of a type now well-known in the art, therefore this mechanism will only be described briefly. The automatic group control is of a kind similar to that described in Patent No. 1,933,308, mentioned above, except that the totals are all printed on a single line instead of on successive lines as in the foregoing patent.

The machine has a major control circuit extending from the supply line 13, through lines 194 and 195 (Figure 1), cam contacts L10, relay magnets 166 and 25, relay contacts 28, held closed by the magnet 25 while cards are being fed, a bus line 35 and a line 34 to the other supply line 12. A similar intermediate circuit extends through cam contacts L11, a magnet 166a, a magnet 26 and contacts 29, held closed by the magnet 26, 140 while a minor control circuit extends through cam contacts L12, a magnet 166b, a magnet 27 and contacts 30 held closed by the magnet 27. The cam contacts L10, L11 and L12 open momentarily at the end of each card cycle, but if there is no change in group, as described in Patent No. 1,933,308, the circuits are maintained through serially connected contacts 191 which are normally open but may be closed by the energization of an associated magnet 190. The magnets 190 are 150

plugged in series with the upper and lower brushes which sense together the holes representing group numbers in two successive cards after the fashion described in Patent No. 1,933,308. For a more 5 detailed description of the plugging of the control circuits to sense changes in group numbers reference may be had to said patent.

The machine is shown in Figure 1 as being set up for major control on two card columns which 10 contain the group number of the cards and consequently the two upper sets of contacts 191 have been plugged in parallel with the cam contacts L10, the remaining contacts 191 being shunted by the closure of switches 193. The upper pair 15 of magnets 190 is plugged each between an upper brush UB reading one of the control columns and the corresponding lower brush LB so that both are energized if the hole configurations of the control columns in two successive cards agree, 20 but not otherwise. Thus, if there is no change in group, both the upper pair of magnets 190 are energized and both the two upper sets of contacts 191 close and remain closed during the rest of the cycle, shunting (with the plugging arrangement shown) the contacts L10 so that the 25 three control circuits are maintained closed. If there is a change in group, however, one or both of the contacts 191 in question remain open and all three control circuits are broken when the 30 cam contacts L10, L11, and L12 open.

The machine may also be plugged for major and minor group control or major, intermediate and minor group control. In case a change occurs in a major group all three control circuits 35 will be broken; a change in an intermediate group results in the intermediate and minor control circuits being broken; while a change in a minor group causes an interruption in the minor circuit only. When one of these circuits is broken 40 the corresponding magnet 25, 26, or 27 is de-energized, opens its contacts 28, 29, or 30, respectively, and closes its contacts 31, 32, or 33, respectively.

When any one or more of these three pairs of 45 contacts 31, 32, and 33 close, a circuit is set up from the supply line 12 through the line 34, the bus line 35, one or more of the contacts 31, 32, 33 in parallel, a line 36, a relay coil 270, the motor control relay magnet MC and a line 37, to 50 the other supply line 13. The relay magnet MC then opens contacts MCC in the motor circuit and brings the motor FM to rest at the end of the last card cycle of a group. Towards the end of this cycle cam contacts L1 close and, in a now 55 well-known manner, initiate total printing cycle by providing a circuit for the reset motor RM and a reset clutch magnet 78. The reset clutch magnet 78 then engages the reset clutch, so that the total shaft turns through one revolution and 60 totals are printed. Magnet 78 also closes contacts 79 to provide a holding circuit for itself from the line 13, through the motor RM, the magnet 78, contacts 79, a line 18 and contacts L2 to the line 12. This circuit is broken at the end of the total 65 taking and resetting cycle by the cam contacts P1 which close as soon as the total shaft starts to turn and short-circuit the magnet 78. The contacts P1 open at the end of the total printing cycle to de-energize the motor RM. During the 70 total printing cycle the contacts LP6, LP7 and LP8 close and energize the magnets 25, 26, 27 so as to set up the automatic control mechanism again. The energization of these magnets normally interrupts the circuit for the relay magnet MC so as to allow of the motor circuit being

re-established, in a known manner, by cam contacts P4.

The magnet 166 normally holds a pair of contacts 51 open but allows them to close when de-energized on the breaking of the major control circuit while the magnets 166a and 166b control similar contacts 51a and 51b. The contacts 51, 51a and 51b can be connected by plug connections 53 to any of the counter resetting clutch magnets 14 and in the present case the contacts 51 are shown as being connected to the magnets 14 associated with the second, third and fourth counters. When the major control circuit fails due to a change in group the magnet 166 becomes de-energized and the contacts 51 close so that a circuit is completed from the main line 12 through contacts LP9, switches 54, the magnets 14 for the second, third and fourth counters, the plug wires 53, and the contacts 51 to the supply line 13. The energization of those three magnets 14 results in engagement of the corresponding counter resetting clutches 206-207 so that these counters are automatically reset after the totals on them have been printed. The engagement of the counter resetting clutches also closes 100 the pairs of contacts 71 and 88 (Figure 2) to condition the counter circuits for printing the totals and asterisks.

When the magnet 16 is energized, its armature closes a pair of contacts 264 (Figures 1 and 8). 105 As soon as the entry control device is restored to its initial position, the contacts 17 are closed and a circuit is set up from the supply line 13 through the motor RM, the reset clutch magnet 78, one winding 68 of the relay magnet 67-68, the contacts 264 and 17 and the cam contacts L2 to the line 12. The winding 68 then closes the contacts 74, which provide a circuit through the winding 67 and the reset magnet 78 and the remainder of the reset circuit. The winding 67 holds the 115 contacts 74 closed until the contacts P1 open and also connects the line 73 to the supply line 13 so that totals will be printed from the counters for which the switches 81 are closed.

Other circuits

The sheet feeding magnet 20 (Figures 1 and 4) is energized, when the magnet 166 becomes de-energized, over a circuit extending from the supply line 12 through cam contacts LP9, the magnet 20, a pair of relay contacts 271, a plug connection 57, and the contacts 51 to the other supply line. The contacts 271 are closed by the magnet 270 which is energized whenever a change of group occurs. It will be noticed that the closure of the contacts 51 resulting from a change of group will complete the circuit through the sheet feed magnet and initiate a sheet feeding operation.

The counting magnet 11 (Figures 1 and 8) of the entry control device is energized over a circuit extending from the supply line 12 through lower card lever contacts LCLC, a switch 15, contacts L8, the magnet 11 and contacts 274 to the other supply line 13. The contacts L8 are closed during listing operation at the "8" point in the card cycle so that the counter receives an impulse and the ratchet wheel is fed through one tooth space during each listing cycle. During total printing cycles the circuit extends through the cam contacts P5 and the magnet 11 receives two impulses, first through upper contacts P5 and then shortly afterwards through the lower contacts P5.

When the entry control device reaches its op-

80

105

110

115

120

125

130

135

erative position, it, as previously explained closes a pair of contacts 45. These contacts are in a circuit extending from the supply line 12, through a switch 70, which is normally closed but can be opened to render the device inoperative, the contacts 45, a relay magnet 273, and a relay magnet 277, to the other supply line 13.

The relay magnets 273 and 277 are also energized when there is a change in group after the antepenultimate or penultimate entries as follows: On the antepenultimate entry the contacts 60 are closed in the manner previously explained. Then, on a change in group, the magnet 270 is energized and closes the contacts 272, 15 while the magnet MC is also energized to open contacts MCC. Also the reset clutch magnet 78 will become energized when the contacts L1 close. The magnet 78 then closes a pair of contacts 278 thereby establishing a circuit for the magnets 20 273 and 277 through the contacts 60, 272 and 278.

The relay magnet 273, when energized, closes holding contacts 276 to provide a holding circuit for the magnets 273 and 277 through the contacts 276 and contacts 265 which are normally closed 25 but (see Figure 8) are opened when the armature 263 is attracted by the reset magnet 16. It is clear, therefore, that the holding circuit will be maintained until the contacts 66 close to reset the entry control device. The relay magnet 273 30 also opens the contacts 274, so as to prevent further energization of the counting magnet 11 and operation of the entry control device, and closes contacts 275.

The closure of the contacts 275, establishes a 35 circuit from the line 13 through the contacts 275, a plug wire 56, the sheet feed control magnet 20, and the cam contacts LP9 to the other supply line 12. The magnet 277 closes a pair of contacts 279 to establish a circuit from the line 13 through the line 37, the magnet MC, a line 280, 40 and the contacts 279, to the line 12. The contacts MCC are then opened by the magnet MC and a total printing cycle follows. The magnet 277 also closes a pair of contacts 84 to connect 45 the line 73 to the line 13 and provides a circuit through the relay winding 67 via the reset clutch magnet 78, etc. The contacts 74 are then closed by the winding 67 and the ensuing cycle becomes a progressive total printing cycle.

50 All total printing cycles that involve a sheet feeding operation and the resetting of the entry control device are to be followed by a progressive total printing cycle initiated by the entry control device.

55 The cam contacts LP6, LP7 and LP8 are arranged to close while the cam contacts P4 are closed so that the control circuits may be re-established and the magnet MC de-energized before the cam contacts P4 open. The de-energization of the magnet MC at this time allows 60 the cam contacts P4 to re-establish the circuit for the motor FM and restart the card feed in the usual manner.

The contacts 90 serve to prevent this energization of the motor FM while the entry control device is being reset and thus prepare the way for the progressive total printing cycle initiated by that device. The contacts 64 close before the contacts LP6, LP7 and LP8 and energize the magnet 65 which closes the contacts 90. 65 The latter maintain the circuit for the magnet MC until after the entry control device has been reset and has closed its contacts 17 to take charge of the circuit of the motor RM. The contacts 70 90 are closed during each resetting of the entry

control device and thus prevent automatic restart of the motor FM through the contacts P4 while the entry control device is being reset.

General operation

80

The operation of the machine will now be explained by means of five specific examples. It will be assumed that the machine is to prepare statements of accounts from a batch of cards each of which carries a number identifying the customer to which the card relates. The cards are sorted into groups by customer's number and the machine is set up as shown in Figure 1 and described before herein, so that, in a well-known manner, the cards containing the customer's number constitute a major group and control the major control circuit to cause it to fail when the customer's number changes.

The intermediate and minor control will not be required and will be put out of action. This is accomplished by closing switches 193 as in Figure 1 and positioning the plug wire 192 as shown.

The record strip is divided into separable sheets each of which can contain ten entries 100 and has space for pre-printed headings. The sheet feeding means is adjusted so that, when operated, it feeds the record strip through a sheet length and the entry control device is adjusted to come into action after 9 entries (i. e. one less 105 than the capacity of a sheet) have been made. Thus when the entry control means comes into action there will still be a blank line, on which either a final or a carry forward total may be printed.

The machine is provided with a listing printing bank in addition to the usual five printing banks associated with counters and the machine is adjusted in a well-known manner so that the customer's number and date are both printed by the 115 listing bank. The printing bank associated with counter No. 1 is set up in a well-known manner to serve as a second listing bank so as to print the invoice number and the code number identifying the transaction. The customer number, 120 date, invoice and transaction numbers are merely printed and their totals are not accumulated in the counters as such totals would be meaningless.

The machine is adjusted in a well-known 125 manner so that all debit amounts are entered into the counter No. 2 and all credit numbers into the counter No. 3. The debit amounts and the complements of the credit amounts are also entered into the counter No. 4 so that this 130 counter contains the balance of the debit and credit amounts. In the present instance the final balance will always be debit so that it is unnecessary to provide a counter for credit balances in which the debit amounts are subtracted 135 from the credit amounts.

The manner in which the balance counter operates and in which the debit and credit amounts are separately dealt with is fully explained in Patent No. 1,896,540 and will not be described 140 herein. The sub-total switches 81 for counters Nos. 2 and 3 will be closed but the sub-total switch for counter 4 will be left open since it is only necessary to carry forward the totals of the credit and debit amounts but not the balance of these two amounts.

The nature of the transaction in the five illustrative examples will be indicated by a number code as follows: 1.—The balance from the previous month, represented by a "balance brought

forward" record card; 2.—A sale of goods or merchandise; 3.—A cash payment on account; 4.—Cash discount.

It will be assumed that the first group of 5 cards relates to customer No. 23 and contains four cards. Then the machine will print the statement shown in Example I, the dotted lines indicating the extent of one sheet.

10

Example I

(Preprinted heading)

15	Cust. No.	Day	Invoice	Trans.	Dr.	Cr.	Bal.
20	23	1	564	1	F		
	23	2	5462	2	5.20		
	23	15	7892	3	25.15		
	23	20	31	4		15.00 2.10 17.10*	13.25*

When the machine makes the fourth entry of the statement on the sixth line, a change in 25 group takes place, and the three control relays 25, 26, and 27 are de-energized completing a circuit from the supply line 12 through the lines 34 and 35, the relay contacts 31, 32, 33 in parallel, the line 36, the relay magnets 270 and MC, 30 and the line 37 to the other supply line 13. The magnet MC then opens contacts MCC in the motor circuit and brings the motor FM to rest and the magnet 270 closes its contacts 271 and 272. The relay magnet 166 is also de-energized and 35 its contacts 51 close. Towards the end of the card cycle the contacts L1 close to initiate a total printing and resetting cycle in the well-known manner. The magnet 11 also receives one impulse during this cycle by closure of contacts 40 L8 whereby to move the dial plate 242 one step.

At the beginning of the reset cycle the contacts LP9 set up circuits which extend (a) from the supply line 12 through contacts LP9, counter resetting clutch magnets 14 for counters Nos. 2, 45 3, and 4, the plug wires 53, and the contacts 51, to the other supply line 13 and (b) from the supply line 12 through the contacts LP9, the magnet 20, the contacts 271, the plug wire 57, and the contacts 51 to the other supply line 13. The 50 energization of the magnets 14 for counters Nos. 2, 3, and 4 results in these counters being coupled to the reset shaft and in their contacts 71 and 88 (Figure 2) being closed and their contacts 72 opened. The machine will thus proceed 55 to print a total from each of these counters, which totals will be identified by asterisks, and thereafter reset the counters.

The energization of the sheet feed magnet 20 by closure of contacts 271 will engage the sheet 60 feed clutch and bring the sheet feeding means into action as described previously. The actual sheet feeding does not, however, occur until the reset shaft begins to turn, which is during the second half of the total printing and resetting 65 cycle and after the printing of totals has been performed.

Thus, the machine will print the total as shown 70 in the seventh line of Example I and during the same cycle will feed the sheet forward until the first line of the next statement is on the printing line.

It should be noted that, at the beginning of 75 this total printing and resetting cycle, the contacts 272 have already been closed by magnet 270 and the reset clutch magnet 78 closes the contacts

278. Later in the cycle the cam contacts P5 close twice to transmit the antepenultimate and penultimate impulses to the counting magnet 11, the first of these impulses causing the pointer of the entry control device to close the contacts 60. Before the contacts 60 close, however, the cam contacts P1 close and shunt the magnet 78 so that its contacts 278 are open when the contacts 60 close. Thus, the magnets 273 and 277 are not energized during the cycle.

Towards the end of this cycle the cam contacts LP 10 close and, since the cam rise 232 of cam 231 on the resetting shaft has already closed contacts 64 as described above, magnet 65 is energized and closes its contacts 63 to establish a holding circuit for itself and also closes contacts 90 to maintain the magnet MC energized. As the reset shaft finally comes to rest, the contacts 64 reopen and the contacts 66 close to provide circuits in parallel with magnet 65 through the contacts 63 and 66, the entry control device reset magnet 16, and solenoid 100. The energization of these latter magnets results in maintaining contacts 90 closed and in the entry control device being reset in the manner 100 previously explained. As soon as the entry control device reaches its starting position the pair of contacts 17 are closed.

During the last half of the total printing and reset cycle and after contacts 90 have been 105 closed, the contacts LP6, LP7, and LP8 also make momentarily and re-establish the circuit through the group control relay magnets 25, 26 and 27, thus closing contacts 28, 29 and 30 and opening the contacts 31, 32 and 33. Normally 110 the opening of the contacts 31, 32 and 33 would interrupt the circuit of magnet MC but the closure of the contacts 90 by the magnet 65 has provided a holding circuit from the supply line 12 through the contacts 90, the line 280, the relay magnet MC and the line 37 to the supply line 13. The contacts MCC thus remain open and prevent restarting the feed motor FM. The closure of the contacts 17 establishes a circuit from the line 12 through the contacts L2, the contacts 115 17 and 264, the winding 68, the reset magnet 78 and the reset motor RM to the other supply line. The winding 68 then closes its contacts 74 to connect the line 73 to the line 13 and a second or progressive total printing cycle now ensues 120 with respect to counters Nos. 2 and 3, which have their switches 81 closed. Counters Nos. 2, 3, and 4 will not be reset since the magnet 166 was energized during the previous total printing 125 cycle and the contacts 51 are therefore open. During the second total printing cycle the asterisk type bar for counters 2 and 3 will be arrested 130 by closure of contacts 89 with the symbol "F" in the printing position, but no totals will be printed. This cycle, therefore, results in the 135 printing of the symbols "F" as shown in the first line of Example II below, and is accompanied by two line spacing movements so that the third line of the statement to be used for the next card group is in the printing position at the end 140 of the cycle. It should be noted that contacts 264 are held closed at the beginning of the second cycle due to the fact that magnets 100, 65 and 16 are all held energized through contacts 66, 63, and LP10 until, later in such second cycle, 145 cam contacts LP10 open long enough to deenergize all three magnets. Obviously contacts LP10 should not reopen until after contacts 79 have closed to establish the shunt circuit around contacts 17, 264. The maintaining of magnet 100 in 150

energized condition during the first part of the second cycle does no harm as magnet 100 is not energized until after the contacts P5 have operated during the first total cycle and is deenergized before contacts P5 operate during the second cycle.

35 At the commencement of the second total printing cycle occurring after the preceding group of cards has been listed the contacts LP10 open and interrupt the circuit through the relay 65 which thereupon allows its contacts 90 to 40 open, interrupting the circuit through the motor control magnet MC and allowing the contacts MCC to close. At the end of the second total printing cycle the circuit for the feed motor FM is re-established in the known manner by closure 45 of the contacts P4 and the machine proceeds to read, accumulate and list the items from the next card group 24.

When the seventh entry of this group is made on the 9th line of the first form or sheet in Example II, the pointer of the entry counting device reaches its ultimate position and closes the contacts 45 (Figures 1 and 8) which completes the circuit through the magnets 273 and 277. Magnet 273 closes its contacts 276 and thus establishes a holding circuit through contacts 276 and the contacts 265 of the entry control device and also opens the contacts 274 to break the circuit for the counting magnet 11 and closes the contacts 275 to energize the statement sheet feeding magnet 20. The magnet 277 closes its contacts 279 and 84, the former contacts energizing the magnet MC, which opens the contacts MCC, and the latter contacts energizing winding 67 which closes the contacts 74. A progressive total printing cycle follows (since the magnet 166 is still energized and holds the contacts 51 open) in which the totals on counters Nos. 2 and 3 are printed together with the symbols "F", but these counters are not reset. As the sheet feeding magnet 20 has been energized, the strip is fed forward during the last half of this cycle to bring a new sheet into position. During the last half of the cycle the contacts 64 and 66 are operated successively by the cam 231 and energize the magnets 65 and 16 and the solenoid 100

so as to reset the entry control device. The magnet 65 closes the contacts 90 to maintain the magnet MC energized while the reset magnet 16 opens the contacts 265 to de-energize the magnets 273 and 277 and closes the contacts 264 to prepare for a progressive total printing cycle which is subsequently initiated by the closure of the contacts 17 by the resetting of the entry control device.

A progressive total printing cycle takes place as explained in connection with Example I and the totals on counters Nos. 2 and 3 are printed with the symbols "F" but these counters are not reset. After this cycle automatic restarting of the motor FM takes place through contacts P4 and the remaining items of group 24 are printed. On the last entry from the group, the automatic group control mechanism comes into action and initiates a total printing and resetting cycle accompanied by a sheet feeding operation and followed by a progressive total printing cycle exactly as explained with reference to Example I resulting in the printing of the symbols "F" on the first line of the following statement.

It will be assumed that the next group 25 contains 7 cards. Then the machine will prepare 100 the statement shown in Example III.

Example III

105 (Preprinted heading)

Cust. No.	Day	Invoice	Trans.	Dr.	Cr.	Bal.

115						

Early in the seventh card cycle required to prepare this statement the cam contacts L8 close 120 giving the ultimate impulse to the counting magnet 11 so that the pointer of the entry control device makes its ultimate step of movement and closes the contacts 45, energizing the magnets 273 and 277, which in turn energize the sheet feed 125 magnet 20 and the magnet MC in preparation for a progressive total printing cycle. Towards the end of the seventh card cycle the cam contacts L10 open and, as there is a change of group, the three control circuits are interrupted so that the 130 contacts 31, 32 and 33 all close. The closure of these contacts will not energize the magnet 270, since it is shunted by the contacts 279 and its contacts 271 and 272 remain open, but the de-energization of the magnet 166 on the failure of 135 the major control circuit results in the contacts 51 closing. The counter resetting clutch magnets 14 for the counters Nos. 2, 3 and 4 are thus energized to engage their clutches, opening the contacts 72 and closing the contacts 71 and 88. 140 The printing magnets are then connected to the supply line 13 by the contacts 71 and are disconnected from the line 73 so that the totals are printed together with asterisk symbols. The counters are also reset. At the end of this cycle 145 the magnets 273 and 277 are de-energized, as the entry control device is reset and a progressive total printing device is initiated exactly as in Example II.

The sequence of operations will now be de- 150

scribed for a case in which the machine is operating under major and minor control and in which a change of minor group occurs at the antepenultimate entry. It will be assumed that the cards 5 are sorted into major groups in accordance with the customer's number and into minor groups in accordance with the transaction numbers. As shown in Example IV major group 30 is divided into minor group 2 containing five cards, minor group 3 containing two cards and minor group 4 containing one card.

The machine is plugged for major control on customer's number and minor control on transaction number, the magnet 14 for counter No. 4 and the contacts 271 being plugged to the contacts 51 and the magnets 14 for counters Nos. 2 and 3 to the contacts 51b. The switches 81 for counters 2, 3 and 4 are all closed. The upper switch 193 in this case will be open and the lower one closed while a plug wire 192a similar to plug 50 wire 192 is inserted in the plug socket 192b, the latter being connected to the series connection between the lower two pairs of contacts 191. The manner in which plugging for major and minor control is effected, is more fully explained in Patent No. 1,933,308, hence further details are unnecessary herein.

In plugging the machine for control by both major and minor group numbers the plug wires are so arranged that the upper two pairs of contacts 60 191 are under control of the holes representing major group number while the third pair of contacts 191 from the top are controlled by the holes representing the transaction number, the lower pair of contacts not being used and being 65 rendered ineffective by the lowest switch 193 (Fig. 1) which is closed.

Early in the fifth card cycle the contacts L8 close and transmit an impulse to the counting magnet 11 which causes the pointer of the entry 70 control device to make its antepenultimate step of movement and close the contacts 60. Towards the end of this card cycle the cam contacts L12 open and, as there is a change from minor group No. 2 to minor group No. 3, the magnets 166a, 166b and 26, 27 are de-energized by the opening 75

of the contacts L12. The contacts 32, 33 therefore close energizing the magnets 270 and MC to stop motor FM and thereby bring about a progressive total printing cycle.

The magnet 166b having been de-energized, 80 the contacts 51b close and energize the counter resetting magnets 14 for counters Nos. 2 and 3, so that these counters will be reset. The magnet 14 for counter No. 4 will not be energized, however, since the magnet 166 is still energized and holds the contacts 51 open, there being no change in the major group. The magnet 270 closes its contacts 271 and 272, but the closure of contacts 271 has no result as the contacts 51 are still open. The magnet MC being energized to hold contacts MCC open and stop the feed motor FM, a circuit is formed through the reset motor RM and the reset clutch magnet 78 when the contacts L1 close, as previously explained. When energized, the magnet 78 closes its contacts 278, thereby completing a circuit from the line 13 through the relay magnets 277 and 273, the contacts 60 (closed when the entry was made on line 7), 272 and 278 and the switch 70 to the line 12. As before, the magnet 273 closes its contacts 276 to provide a holding circuit and its contacts 275 to energize the sheet feed magnet 20 and opens its contacts 274. The magnet 277 closes its contacts 84, energizing the winding 67, which closes the contacts 74 and connects the line 73 to the line 13.

The magnet 277 also closes its contacts 279, shunting the magnet 270 and the contacts 271 and 272 open. The opening of the latter contacts does not deenergize the magnets 277 and 273, 110 since the contacts 276 and 265 are closed.

A combined total printing and resetting cycle and progressive total printing cycle follow in which the printing circuits for counters Nos. 2 and 3 are supplied from the line 13 through the contacts 71 and these counters are reset and in which the printing circuits for counter No. 4 are supplied from the line 13 through the contacts 74 and 84 in parallel, the line 73, the switch 81 and contacts 72 of this counter, but counter No. 4 is not reset, and the eighth line of Example IV is thus printed. The record-strip is then fed forward by the sheet feeding device to bring the first line of the next sheet to printing position, the entry control device is reset, and a progressive 115 total printing cycle initiated exactly as in Example II. As counters Nos. 2 and 3 have been reset only the balance on counter No. 4 is printed and the sheet is spaced two lines.

The two items of minor group 3 are printed 130 and a change of minor group takes place after the entry on the fourth line of this sheet. The magnets 166b and 27 become de-energized so that the machine performs a total printing and resetting cycle in which the totals on counters Nos. 135 2, 3 and 4 are printed on the fifth line of this sheet and counters Nos. 2 and 3 are reset. Two line spacing movements occur so that the single item of the minor group No. 4 is printed on the seventh line. The sheet feeding magnet will 140 not be energized during the total printing cycle just mentioned as the contacts 51 and 275 remain open. The contacts 275 cannot close since neither the contacts 45 nor contacts 60 have been closed. Consequently, closure of contacts 271 145 and 272 by the energization of relay 270 has no effect on relay 273 which closes contacts 275.

A change in the major group then occurs and all three control circuits fail so that the magnets MC and 270 become energized and the contacts 150

51 and 51b close to energize the counter resetting clutch magnets 14 of counters Nos. 2, 3 and 4. As an entry has been made in the seventh or antepenultimate line the contacts 60 are closed 5 so that the ensuing cycle is similar to that occurring at the end of the first sheet of Example IV, except that the balance on the counter No. 4 is printed with an asterisk instead of an "F" and this counter is reset as well as the counters 10 Nos. 2 and 3.

If a change in major or minor group occurs on the penultimate entry the sequence of operations is similar to that described with reference to Example III, therefore, it need not be described. It 15 will be seen that the machine prints a carry forward total on the ultimate entry being made if there is no change in major group and will also print a carry forward major total (if required) 20 on a change in minor group after the antepenultimate, penultimate or ultimate entry.

The machine may also be operated under tabulating conditions, that is to say, only the totals of a series of major and minor groups are to be printed with each major group on a separate 25 sheet as far as possible. The machine is suitably plugged and adjusted to tabulate in a well-known manner. With this adjustment only a single line spacing operation occurs when a total is printed and a switch 15 (Figure 1) is opened 30 to disconnect the contacts L8 and lower cam contacts P5 from the line 12. The counting magnet 11 thus receives a single impulse through the upper cam contacts P5 during each total printing cycle.

35 The entry control device is adjusted to give one more entry than the capacity of the sheet, that is to say, if the sheet has 10 lines, as in the previous examples, the entry control device is adjusted to eleven lines.

40 Example V, illustrates a case in which major group 11 contains more than ten minor groups.

Example V

Major group No.	Minor group No.	Minor total	Major total
50 11.....	1.....	120.00*	F
11.....	2.....	30.00*	
11.....	3.....	15.00*	
11.....	4.....	32.00*	
11.....	5.....	7.00*	
11.....	6.....	39.00*	
11.....	7.....	110.00*	
11.....	8.....	72.00*	
55 11.....	9.....	96.00*	521.00 F

Major group No.	Minor group No.	Minor total	Major total
60 11.....	10.....	F	521.00 F
65 11.....	11.....	16.00*	
	Etc.	23.00*	

The contacts 60 will be closed by the entry control device on the ninth impulse being transmitted to the magnet 11, that is, during the printing of the total of minor group No. 8. On the change from minor group 8 to minor group 9 the minor control circuit fails, energizing the magnets 270 and MC. The magnet 270 closes its contacts 272

while the energization of the magnet MC results in the reset motor RM and the reset clutch magnet 78 being energized. The latter then closes its contacts 278. A total printing and reset cycle follows in which first the cam contacts P1 close and de-energize the magnet 78 so that the contacts 278 open and afterwards the upper cam contacts P5 close and energize the magnet 11. The entry control device, thereupon, advances one step and closes the contacts 60, but, as the contacts 278 are now open the relay magnets 273 and 277 are not energized.

The machine therefore resumes tabulating with minor group No. 9 on the conclusion of this cycle.

At the end of minor group No. 9 the minor control circuit is again broken and the magnets MC and 270 are energized. The magnet 270 closes its contacts 272, and, as the contacts 60 are now closed, the relay magnets 273 and 277 are energized when the contacts 278 close on the commencement of the total printing cycle. The total of minor group No. 9 and a carry forward major total are then printed on line 10 of the sheet, a new sheet is fed to the platen, the entry control device is reset and a progressive total printing cycle is initiated all in the manner explained in connection with Example IV. The machine then resumes tabulating operations with the remaining cards of major group No. 11. At the end of a major group a total printing and resetting cycle occurs in which both the minor total and the major total are printed on the same line and all the counters are reset. If the ninth minor group of Example V had been the last group of the major group, the cycle of operation 110 would have been the same except that the major total would have been identified by an asterisk instead of an F and the counter containing it would have been reset.

The printing of the characters "F" and "*" in some instances without accompanying totals serves as an accumulator "clear" signal indicating that the accumulators which printed such symbols were properly cleared of totals preparatory to accumulating a new series of items and printing the totals thereof.

This invention has been illustrated and described by means of a specific form of embodiment and as applied to a particular type of record controlled accounting and statistical machine solely for the purpose of illustrating the principle of the invention and how it may be applied in practice. It is desired to point out, however, that the invention is not limited to the specific form of embodiment or machine selected for illustration as it may be varied as to form or details or applied to other types of machine equally as well, according to circumstances.

What I claim is

1. An accounting machine including an accumulating mechanism, entering devices for entering amounts therein to be added, total recording means and sheet feeding means for feeding record forms to said total recording means, means for automatically calling the total recording means into operation after the entry of a predetermined number of items to record a progressive total, means for initiating operation of said sheet feeding means under control of the total taking means to feed a new form into record receiving position after each progressive totaling operation and means for again calling said total taking means into operation to repeat the progressive total on the new sheet.
2. A record controlled machine comprising

- recording mechanism operable to record a series of items successively upon record sheets of predetermined length and the total of said items at the end of said series, means for calling the recording mechanism into action to record a progressive total after a predetermined number of items have been recorded, sheet feeding means controlled by the recording mechanism for feeding a new sheet into position to receive further entries and adapted to control the recording mechanism to initiate a progressive total recording cycle on the completion of a sheet feeding operation whereby to record the total of the items entered on the first sheet at the head of the new sheet.
3. In a record controlled machine, printing mechanism, mechanism adapted to feed a predetermined length of record medium to the printing zone, means for predetermining the number of imprints to be made on said length of record medium, total taking mechanism for controlling the printing mechanism to print a total at the end of a series of imprints on said length of record medium, means controlled by the first named means for initiating a progressive total printing cycle when the number of imprints to be made exceeds the capacity of said length of record medium, means controlled by the total taking mechanism for initiating an operation of the sheet feeding mechanism to feed a new length of record medium to receive the remainder of the imprints, and means jointly controlled by the total taking mechanism and sheet feeding mechanism for initiating a second progressive total printing cycle whereby to again print said total at the head of the new length of record medium.
4. A record controlled machine comprising total taking mechanism, means for calling the total taking mechanism into action to record a total after a predetermined number of items have been entered on a record medium, means controlled by the total taking mechanism for feeding a new record medium into recording position, and means controlled by the feeding means for again calling the total taking mechanism into action to record the total at the head of the new record medium.
5. A record controlled machine comprising sheet feeding mechanism for feeding a record sheet into position to receive successive entries, means for recording a total of the entries, an entry control device settable to become effective after a predetermined number of entries have been made on the sheet to call into action the total recording mechanism, automatic group control mechanism, means jointly controlled by the group control mechanism and the entry control device for prematurely calling into action the total recording mechanism, and means controlled by the total recording mechanism for initiating a cycle of operation of the sheet feeding mechanism.
6. In a record controlled machine, mechanism for printing items on a series of blank forms, sheet feeding mechanism for feeding one of said forms into position to receive imprints from said printing mechanism, an entry control device selectively settable to predetermine the number of entries to be printed on each form, total taking mechanism for controlling the printing mechanism to print a progressive total at the end of a series of entries on said form, means controlled by the entry control device for initiating a progressive total printing cycle when the number of entries to be made exceeds the capacity of said form, and means controlled by the total taking mechanism for initiating an operation of the sheet feeding mechanism whereby to feed a new form into position to receive the remainder of the entries.
7. A record controlled machine comprising item entering mechanism for entering items on a record sheet, total recording mechanism adapted to record on each sheet the total of the items entered on each sheet, sheet feeding mechanism for feeding record sheets into position to receive items and totals, and means for initiating an uninterrupted succession of cycles of the total taking mechanism and sheet feeding mechanism after a predetermined number of entries have been made on a sheet, said succession of cycles consisting of two cycles of the total recording mechanism with an intervening sheet feeding cycle.
8. A record controlled machine comprising means for entering items on a record sheet, means for recording totals of said items on said sheet, means for feeding record sheets into position to receive items and totals, means for automatically initiating an operation of both the sheet feeding means and the total recording means after a predetermined number of items have been entered on a sheet, and means for automatically initiating a second operation of the total recording mechanism prior to entering items on each sheet.
9. A record controlled machine comprising total recording mechanism, means to initiate an operation of the total taking mechanism after a certain number of entries have been made on a record medium, means called into operation as an incident to a total recording operation to feed a new record medium to the total recording mechanism after the latter has operated once in accordance with control by the initiating means, and means to compel a second operation of the total recording mechanism as a preliminary to making entries on the new sheet.
10. A record controlled machine comprising means for recording totals of items entered on a record medium, which record medium may consist of a continuous web adapted to be separated into individual sheets; means for predetermining the number of items to be entered on a given section of said record medium comprising a sheet, means controlled by the predetermining means for initiating two successive repeat cycles of the total recording means, and feeding means operating as an incident to one of said cycles for feeding the record medium a predetermined length between the respective recordings of the first and second totals whereby to bring a new section of the record medium into position for the recording of the second total.
